J. KROTOWYCH.
WINDOW CURTAIN AND SHADE SUPPORT.
APPLICATION FILED APR. 22, 1920.

1,353,122.

Patented Sept. 14, 1920.

UNITED STATES PATENT OFFICE.

JHAN KROTOWYCH, OF LILLIAN, WEST VIRGINIA.

WINDOW CURTAIN AND SHADE SUPPORT.

1,353,122.

Specification of Letters Patent. Patented Sept. 14, 1920.

Application filed April 22, 1920. Serial No. 375,872.

To all whom it may concern:

Be it known that I, JHAN KROTOWYCH, citizen of Poland, residing at Lillian, in the county of Barbour and State of West Virginia, have invented certain new and useful Improvements in Window Curtain and Shade Supports, of which the following is a specification.

This invention relates to window curtain supports, having more particular reference to a combination support for the usual vertically adjustable curtain or shade and the inner laterally movable draperies.

The invention has for an object to provide an improved and novel combination support, and specifically to provide a novel means for mounting the curtain pole from which the inner curtains or draperies are suspended.

For further comprehension of the invention, and of the objects and advantages thereof, reference will be had to the following description and accompanying drawings, and to the appended claims in which the various novel features of the invention are more particularly set forth.

Figure 1 of the drawings is a face view showing a window having the invention applied thereto.

Fig. 2 is a side edge view, showing the wall structure in section.

Fig. 3 is a fragmentary horizontal section taken on the line 3-3 of Fig. 4.

Fig. 4 is a fragmentary transverse vertical section on the line 4-4 of Fig. 1.

Fig. 5 is a detail vertical section taken on the line 5-5 of Fig. 3.

Fig. 6 is a fragmentary transverse vertical section taken on the line 6-6 of Fig. 1.

In the drawings 10 indicates generally the facing strip of a frame of a window of ordinary construction, the window sashes being indicated at 11. In constructing my improved window curtain support I preferably provide an ornamental top or head-board 12 which extends from side to side of the window frame and is preferably supported at a distance in front of the wall structure 13 on the ends of rigid hooks 14

screwed into the wall structure and braced by down-turned feet 15, the outer ends of the hooks engaging in eyes 16 carried by the head-board. These hooks 14 are preferably located at a distance from the ends of the head-board as shown in Fig. 1, wooden strips or bars 17 extending from the ends

of the head-bar 12 rearwardly across the top edge of the facing strip 10 to which they may be secured.

These side bars 17 have the window curtain supporting means mounted thereon as will now be set forth, 19 indicating the usual spring roller, and 20 the curtain pole. To support the spring roller 19 one of the side bars has mounted thereon a socket element 65 21 having a circular socket aperture to receive the usual round trunnion at one end of the spring roller. The other side bar has fixed thereto a plate 22 having a slot 23 formed therein to receive the square trunnion on the corresponding end of the spring roller 19, this slot extending first upwardly, adjacent one side edge of the plate, then horizontally and finally downwardly a short distance, this inner portion providing a 75 socket in which the square trunnion rests and is held against rotation as indicated in Fig. 4.

The curtain pole is preferably formed with diminished ends 25, one of said ends 80 being adapted to engage in a socket aperture 26 formed in an angular bracket 27 fixed on the side bar 17 which has the socket element 21 fixed thereon. The opposite end of the pole 20 is supported by the following 85 means which permits its ready removal or attachment while at the same time insuring against accidental displacement.

This means comprises an angular plate 30 extending across the bottom and inner faces 90 of the side bar on which the plate 22 is mounted and covering a recess 31 in the said side bar. Upon the bottom flange of this plate a latch 32 is pivoted at one end to swing horizontally in the recess 31, this 95 latch being preferably of angular shape in cross section with one flange resting upon and pivoted to the bottom flange of the plate 30 and its other flange extending upwardly on the side adjacent the vertical 100 flange on the plate. This latch is normally pressed outwardly against the said vertical flange of the plate 30 by a flat spring 33 located in the recess 31 and secured at one end to a post 34 on the plate and bearing 105 at its opposite end against the vertical flange of the latch. Formed in the plate 30 is a slot 35 which extends partly through both flanges thereof, extending upwardly in the vertical flange a sufficient distance above 110 the latch 32 to allow of the end of the curtain pole resting on the latter when in the

slot. The latch 32 is provided with a handle 36 which projects through a slot 37 in the plate so as to permit of the latch being pressed inwardly by hand against the action of spring 33. The adjacent diminished end of the curtain pole 20 is preferably of square cross-section and beveled off as shown in Fig. 5 and the parts are so proportioned that when the opposite end is inserted in the aperture 26 this beveled end will engage and push back the latch automatically when it is moved upwardly into the slot, the latch swinging outwardly again when the said end is moved to the top of the slot and thereby supporting the curtain pole. It is believed that the above description will make the manner of attachment and removal apparent, one end of the curtain pole being inserted into the socket aperture 26 and the opposite end being brought into registry with the slot 35 and then pushed upwardly therein. To remove the curtain pole it is only necessary to push the handle 36 backward, freeing the latch from the end of the curtain pole and allowing the latter to drop.

Having thus described my invention what I claim as new and desire to secure by Letters Patent of the United States is as follows:

- 30 1. In a window curtain support, a head-board having at the ends a pair of rearwardly extending side bars, and curtain pole supporting devices on said side bars, one of said devices including a spring-pressed pivoted latch adapted to engage under the end of the curtain pole.
2. In a window curtain support, a head-board having at the ends a pair of rearwardly extending side bars, and curtain pole supporting devices on said side bars, one of said devices including a spring-

pressed pivoted latch adapted to engage under the end of the curtain pole, and a plate covering a recess in the side bar in which said latch is located, said plate being vertically slotted for passage of the end of the curtain pole. 45

3. In a window curtain support, a head-board having at the ends a pair of rearwardly extending side bars, and curtain pole supporting devices on said side bars, one of said devices including an angular plate extending across the bottom and inner face of the side bar and covering a recess in the said bar, a latch pivoted on the horizontal flange of said plate, a spring pressing said latch against the vertical flange of said plate, said plate having a slot extending partly along the horizontal flange of the plate and partly up the vertical flange 60 of the plate.

4. In a window curtain support, a head-board having at the ends a pair of rearwardly extending side bars, and curtain pole supporting devices on said side bars, one of said devices including an angular plate extending across the bottom and inner face of the side bar and covering a recess in the said bar, a latch pivoted on the horizontal flange of said plate, a spring pressing said latch against the vertical flange of said plate, said plate having a slot extending partly along the horizontal flange of the plate and partly up the vertical flange 70 of the plate, the end of the curtain pole being beveled to engage and move said latch when the said end is moved upwardly in the said slot. 75

In testimony whereof I have affixed my signature.

JHAN KROTOWYCH.
